UNITED STATES PATENT OFFICE.

VICTOR HUGHES, OF DAYTON, OHIO, ASSIGNOR TO GENERAL MOTORS RESEARCH CORPORATION, OF DAYTON, OHIO, A CORPORATION OF DELAWARE.

SPRING CONSTRUCTION.

Application filed October 3, 1923. Serial No. 666,219.

This invention relates to improvements in springs and more particularly to that type of springs used in connection with motor vehicles.

5 It is among the objects of the present invention to hold one end of a spring assembly, including a plurality of spring blades in stacked relation, in position, whereby relative longitudinal movement of the blades 10 is prevented without providing holes in the blades which would tend to weaken them.

Further objects and advantages of the present invention will be apparent from the following description, reference being had to 15 the accompanying drawing wherein preferred embodiments of the present invention are clearly shown.

In the drawings:

20 Fig. 1 shows a spring including the preferred form of spring structure. The clamping element of the spring as well as the front axle to which one end of spring is attached are shown in section.

25 Fig. 2 is a view similar to Fig. 1 showing a modified form of construction of the spring.

Referring to the drawing the numeral 20 designates the frame of the automobile to which is secured the spring supporting 30 bracket 21. This bracket 21 includes a channel portion 22 in which the other end of the spring 23 is adapted to rest. One end of the channel 22 is secured to a post 24 by means of a stud 25, this stud also securing the post 24 to the frame 20. U bolts 26 are associated with the bracket 21 in such a manner so that when nuts 27 are screwed in position on the U bolts and tightly drawn up, this end of the spring 23 will be rigidly held 40 in position in the bracket and channel members. The lower blade 23a of the spring 23 is secured to the front axle 28 in any suitable manner. The free ends of the spring blades making up the spring 23 are prevented 45 from moving sidewise by both the side walls of the channel members 22 and also by means of a clip 29 surrounding the four lower blades of the spring 23 near their free ends.

50 The ends of the spring blades adjacent to the bracket 21 are each provided with an up turned portion 30, the outer surface of each of the upper blades fitting into the inner surface of the turned up end of the next 55 adjacent lower blade, while the outer sur-

face of the turned up end of this second blade fits inside the inner surface of the turned up edge of the third blade and so on for the entire blade assembly. The outer surface of the turned up edge of the lowest 60 blade 23a abuts against the projection 31 formed on the inside surface of the bottom of the channel member 22, thereby preventing longitudinal movement of the lower blade in this direction. The curved or 65 turned up ends of the blade being nested in each other as has been mentioned heretofore will thus prevent longitudinal movement of the spring blades toward the post 24 of the channel member 22. The inner 70 edge of the turned up portion of the upper spring blade abutting against the edge of the bracket 21 will prevent longitudinal movement of the spring blades in the opposite direction or toward the axle 28. In the Fig. 75 2 a similar spring is shown, the spring blades however instead of having turned up edges as are shown in Fig. 1, have bulges 40 provided at their ends, the end of the bulges on one spring engaging with the forward 80 edge of the bulge of its next lower adjacent spring. In this case the lowest spring has its end abutting against the projection 41 formed on the channel member 22 which prevents longitudinal movement of the spring 85 assembly in this direction.

The advantage of using the structure of this type in vehicle spring resides in the fact that no holes are formed in the springs for receiving bolts or studs to prevent longitudinal displacement of the blade members. Providing holes in spring blades will 90 tend to weaken the spring.

While the forms of embodiments of the invention as disclosed constitutes preferred 95 forms, it is to be understood that other forms might be adopted, all coming within the scope of the claims which follow.

What I claim is as follows:

1. In a spring device for motor driven 100 vehicles and in combination with a spring supporting bracket, a spring made up of a plurality of leaves arranged one upon another, and the extremities of which are provided with abutments in engagement with one another throughout the end of the spring; a stop carried by said bracket, and which stop is engaged by the abutment of the upper of said leaves to thereby prevent longitudinal movement of said upper leaf; 110

a fixed member independent of said bracket and secured to said frame at a point spaced apart from said bracket, and which member extends beneath the end of the 5 spring; means for clamping the end of the spring between said bracket and said fixed member; and a second stop carried by said fixed member and with which the abutment of the lower one of said leaves engages to 10 thereby prevent longitudinal movement of said lower leaf.

2. In a spring device for motor driven vehicles and in combination with a frame member, and a spring supporting bracket 15 carried thereby; a spring made up of a plurality of leaves arranged one upon another, and the extremities of which are bent to provide abutments in engagement with one another throughout the end of the spring; 20 a stop carried by said bracket, and which stop is engaged by the bent abutment of the upper of said leaves to thereby prevent longitudinal movement of said upper leaf; a member independent of said bracket and 25 fixedly secured to said frame member at a point spaced apart from said bracket, and which member extends beneath the end of said spring; means for clamping the end of the spring between said bracket and said 30 fixed member; and a second stop carried by said fixed member, and with which the bent

abutment of the lower one of said leaves engages to thereby prevent longitudinal movement of said lower leaf.

3. In a spring device for motor driven vehicles and in combination with a frame member, and a spring supporting bracket carried thereby; a channel member secured to said frame member and the free end of which lies adjacent said bracket; a spring 35 one end of which lies between said bracket and said channel member and which spring is made up of a plurality of leaves arranged one upon another, and the extremities of which leaves are provided with abutments 40 in engagement with one another throughout the end aforesaid of the spring; a stop carried by said bracket, and which stop is engaged by the abutment of the upper of said leaves to thereby prevent longitudinal movement of said upper leaf; means for clamping 45 said bracket, said channel member, and the end aforesaid of the spring between them together; and a second stop carried by said channel member and with which 50 the abutment of the lower one of said leaves engages to thereby prevent longitudinal movement of said lower leaf.

In testimony whereof I hereto affix my signature.

VICTOR HUGHES.
